PAIR OF PRISM SPECTACLES

Clarence S. Warner, Boston, Mass., assignor to
American Prismatic Glasses Incorporated, Bos-
ton, Mass., a corporation of Massachusetts

Application November 8, 1950, Serial No. 12,904

Term of patent 14 years

(Cl. D57—1)

To all whom it may concern:

Be it known that I, Clarence S. Warner, a citizen of the United States of America, residing at Boston, in the county of Suffolk and Commonwealth of Massachusetts, have invented a new, original, and ornamental Design for a Pair of Prism Spectacles, of which the following is a specification, reference being had to the accompanying drawing, forming a part thereof.

Figure 1 is a plan view of a pair of prism spectacles embodying my novel design;

Figure 2 is a bottom plan view of the same;

Figure 3 is a side elevation of the same;

Figure 4 is a front elevation of the same; and

Figure 5 is a rear elevation of the same.

I claim:

The ornamental design for a pair of prism spectacles, as shown.

CLARENCE S. WARNER.
